(57) **CLAIM**

The ornamental design for a vehicle grille, as shown and described.

DESCRIPTION

FIG. 1 is a front perspective view of the vehicle grille;

FIG. 2 is an left elevational view of the grille;

FIG. 3 is a right elevational view of the grille;

FIG. 4 is a top plan view of the grille;

FIG. 5 is a bottom plan view of the grille;

FIG. 6 is a front elevational view of the grille; and,

FIG. 7 is a rear elevational view of the grille.

The broken lines shown in the FIG. 1 drawing view are for illustrative purposes only and form no part of the claimed design.
